DESK TELEPHONE

Charles F. Mattke, Fanwood, N.J., assignor to Bell Telephone Laboratories, Incorporated, New York, N.Y., a corporation of New York

Filed July 16, 1962, Ser. No. 70,931

Term of patent 14 years

(Cl. D26—14)

FIG. 1

FIG. 2

FIG. 3

FIG. 1 is a front elevational view of a desk telephone, showing my new design;

FIG. 2 is a side elevational view, the opposite side being substantially a mirror image thereof; and

FIG. 3 is a perspective view thereof.

The characteristic features of the design are shown in full lines. The bottom surfaces of the desk telephone are essentially flat and the rear surface follows the general contours shown in the side view.

I claim:

The ornamental design for a desk telephone, as shown and described.
